UNITED STATES PATENT OFFICE.

DAVID LOWE CLOUD, OF GREENSBORO, GEORGIA.

CABINET AND STERILIZER.

1,032,882.

Specification of Letters Patent.

Patented July 16, 1912.

Application filed September 30, 1911. Serial No. 652,119.

To all whom it may concern:

Be it known that I, DAVID L. CLOUD, a citizen of the United States, residing at Greensboro, in the county of Greene and 5 State of Georgia, have invented a new and useful Cabinet and Sterilizer, of which the following is a specification.

This invention relates to cabinets and has for its object to provide an improved 10 cabinet adapted especially for dentists or dental students which can be compactly folded in a novel manner when not in use and in which the instruments of a dentist or student can be kept, or in which the instruments can be sterilized.

With the above and other objects in view this invention is embodied in the novel construction, arrangement and combination of parts as hereinafter described and as shown 20 in the accompanying drawings, in which similar reference characters indicate similar parts, and in which,—

Figure 1 is a perspective view of the cabinet in open position. Fig. 2 is a vertical 25 section thereof in closed or folded position. Fig. 3 is a perspective view of one of the trays or tills.

Referring specifically to the drawings, the casing or body of the cabinet comprises 30 sides 11, back 12, bottom 20 and a table top 6, the front being open to form a door-way. Horizontally swinging doors 10 are hinged to the front edges of the respective sides 11 and a door 14 is mounted to swing vertically to the front edge of a bottom 20 by 35 hinges 15. The doors 10 when swung inward are adapted to pass between the top and bottom to close the doorway and the door 14 when swung upward is arranged to 40 swing over the doors 10 and front edges of the sides 11 and under the top 6. A catch 16 carried by the free end of the door 14 is adapted to snap into the socket 9 on the 45 front edge of the top 6 to retain the doors in closed or folded position.

An extension 5 is mounted to one side of the table top 6 by means of the hinges 8 to lie in the plane of the table top when 50 opened and which is of a size to fit neatly over the table top when folded thereon. Eyes 7 are disposed at the front and rear edges of the extension 5 near the free end thereof and a hook 17 is carried by the free end of the door 14 which is adapted to engage the eye on the front side of the extension upon the door and extension being

folded to retain the parts in position. A supplemental hook 17' is also provided at the rear of the cabinet to engage the eye on the rear end of the extension 5. A handle 60 21 is secured to the outer face of extension 5 and serves as a means for carrying the cabinet when folded.

This cabinet when folded or closed is compact in construction and may be readily 65 carried or conveyed about.

A plurality of trays or tills 18, 18^a, 18^b, and 18^c are hinged to the respective inner and outer edges on the inner sides of the door 10 by hinges, 19, 19^a, 19^b and 19^c, respectively, 70 and are all arranged in different horizontal planes. These trays have perforated bottoms for convenience in sterilizing the instruments held in the trays or tills. The trays or tills hinged to the outer edges 75 of the doors 10 may be swung when the doors are being closed to prevent their striking the opposite door and they can be conveniently swung when the doors are open for convenience in selecting the instruments therefrom or replacing the instruments therein. The trays 18^b and 18^c which are hinged to the inner edges of the doors 10 on the inner sides thereof are 80 adapted to fit between the sides of the casing and the said doors, when the doors are closed, to prevent the excessive inward movement of the doors, and the trays 18 and 18^a which are hinged to the outer edges of the doors on the inner sides thereof 85 project into the path of the opposite doors, whereby the said doors are required to be opened and closed simultaneously. These trays 18 and 18^a are also adapted to swing behind the opposite doors 10, when the 90 doors 10 are closed, thereby tending to retain the doors in closed position, but permitting the doors to be opened by the application of sufficient force.

A partition 13 is arranged at the rear of 100 the bottom 20 to form a medicine case for bottles of medicine or other objects.

When the door 14 is extended or swung open the same forms a suitable base for tools, instruments or other articles and the 105 hooks 17 and 17' being released from the eyes 7 permit the extension 5 to be swung open to combine with the table top 6 to form a table of suitable area. When the extension 5 is folded on the top 6 the surfaces which are used are swung together to 110 protect the same from exposure to dust and

other objectionable matter, which is also true of the door 14 when swung upward against the door 10.

The cabinet as provided in this construction is simple and substantial and is convenient in use. The body, doors and extension are all preferably made of wood and the cabinet has a neat appearance and when closed is dust proof. Thus when folded together the cabinet may be conveniently carried or conveyed about and is compact in construction, and whenever desired the same can be readily opened for use.

What is claimed is:—

- 15 1. In a cabinet of the character described, a casing having its front open to form a doorway, horizontally swinging doors hinged to the front edges of the sides of the casing and adapted to swing between the top and bottom to close the doorway, trays hinged to the outer edges of the said doors on the inner sides thereof, the said trays projecting into the paths of the opposite doors, whereby the said doors are required 25 to be opened and closed simultaneously, a vertically swinging door hinged to the front edge of the bottom and adapted to swing over the said doors and the front edges of the sides of the casing and under the top thereof, and means for retaining the vertically swinging door in closed position.
- 20 2. In a cabinet of the character described, a casing having its front open to form a doorway, horizontally swinging doors hinged to the front edges of the sides of the casing and adapted to swing between the top and bottom to close the doorway, trays hinged to the inner edges of the said doors on the inner sides thereof, the said trays being 30 adapted to fit between the sides of the casing and the said doors when the doors are closed to prevent the excessive inward movement of the doors, a vertically swinging door hinged to the front edge of the bottom and adapted to swing over the said doors and the front edges of the sides of the casing and under the top thereof, and means for retaining the vertically swinging door in closed position.
- 25 3. In a cabinet of the character described, a casing having its front open to form a doorway, horizontally swinging doors hinged to the front edges of the sides of the casing and adapted to swing between the top and bottom to close the doorway, trays hinged to the inner edges of the said doors on the inner sides thereof, the said trays being 40 adapted to fit between the sides of the casing and the said doors when the doors are closed to prevent the excessive inward movement of the doors, a vertically swinging door hinged to the front edge of the bottom and adapted to swing over the said doors and the front edges of the sides of the casing and under the top thereof, and means for retaining the vertically swinging door in closed position.

ed to fit between the sides of the casing and the said doors when the doors are closed to prevent the excessive inward movement of the doors, and the trays hinged to the outer edges projecting into the paths of the opposite doors, whereby the said doors are required to be opened and closed simultaneously, a vertically swinging door hinged to the front edge of the bottom and adapted to swing over the said doors and the front edges of the sides of the casing and under the top thereof, and means carried by the front edge of the top of the casing and the free end of the latter door to retain the said door in closed position.

3. In a cabinet of the character described, a casing having its front open to form a doorway, horizontally swinging doors hinged to the front edges of the sides of the casing and adapted to swing between the top and bottom to close the doorway, trays hinged to the inner edges of the said doors on the inner sides thereof, the said trays being adapted to fit between the sides of the casing and the said doors when the doors are closed to prevent the excessive inward movement of the doors, a vertically swinging door hinged to the front edge of the bottom and adapted to swing over the said doors and the front edges of the sides of the casing and under the top thereof, and means for retaining the vertically swinging door in closed position.

In testimony that I claim the foregoing as my own, I have hereto affixed my signature in the presence of two witnesses.

DAVID LOWE CLOUD.
